[57] CLAIM

The ornamental design for a baseball equipment storage rack, as shown and described.

DESCRIPTION

FIG. 1 is a perspective view of a baseball equipment storage rack showing our new design;

FIG. 2 is a front elevational view thereof, the rear being plain and unornamented;

FIG. 3 is a left side elevational view thereof, the right side being a mirror image of that shown;

FIG. 4 is a top plan view thereof; and,

FIG. 5 is a bottom plan view thereof.
